Application November 10, 1947, Serial No. 142,444

Term of patent 3½ years

(Cl. D48—20)

To all whom it may concern:

Be it known that I, Irving I. Gotliffe, a citizen of the United States, residing at New York, in the county of New York and State of New York, have invented a new, original, and ornamental Design for a Head for a Floor Lamp Column, of which the following is a specification, reference being had to the accompanying drawings, forming a part thereof.

In the drawings:

Fig. 1 is an elevational view of a head for a floor lamp column showing my new design. The ornamentation of the portion shown in dotted lines is a repetition of the portion shown in full lines.

Fig. 2 is a top plan view thereof.

I claim:

The ornamental design for a head for a floor lamp column, as shown and described.

IRVING I. GOTLIFFE.
